GIRDLE CONSTRUCTION

Ethel R. Kaupp, New York, N. Y.

Application November 1, 1948, Serial No. 57,780

5 Claims. (Cl. 2-28)

1

The present invention relates to a girdle construction and it particularly relates to a novel method of constructing women's girdles.

It is among the objects of the present invention to provide a novel girdle construction giving increased foundation support to the female figure and also enhancing the support given to the waist and lower part of the upper body.

Another object of the present invention is to provide an improved girdle construction which will give enhanced support to the figure and at the same time which may be more readily constructed of elastic material so as to give maximum support with minimum discomfort.

A further object is to provide a novel girdle construction and procedure for making the same which will enable better shaping of the girdle to the human body.

Still further objects and advantages will appear in the more detailed description set forth below, it being understood, however, that this more detailed description is given by way of illustration and explanation only and not by way of limitation, since various changes therein may be made by those skilled in the art without departing from the scope and spirit of the present invention.

In accomplishing the objects of the present invention, the girdle is caused to extend across the waist with a section forming a cuff or funnel or inverted cone gathered and supporting the body at both sides of and in a zone above the waist. The lower part of the girdle at the same time, by suitable gathering and sizing of the material, will support the body most comfortably below the waistline and give maximum support with minimum discomfort.

In a preferred form of the invention, the upper cuff or trans-waistline section is formed of two front and two rear panels with the lower part of the cuff coinciding with the waistline at the sides of the body and extending substantially below the waistline at the front and back of the body.

Desirably, each section is provided with an oblique supporting bone element and the cuff sections are gathered together at the top in the rear and at the bottom in the front. The bottom of the cuff at both the front and the back of the body extends below the waistline, such extension being substantially greater in the front than in the rear.

The foundation body itself below the waistline and around the thighs is desirably formed of four sections in the front and three sections in

2

the rear, with the middle of the sections each being gathered in the front and the upper and lower ends of the rear sections being also gathered to form most adequate support.

Whereas, all four elements of the cuff have both horizontal and vertical stretch, only the front and back panel sections of the body support member have vertical stretch while the side panels have up and down as well as transverse stretch.

With the foregoing and other objects in view, the invention consists of the novel construction, combination and arrangement of parts as hereinafter more specifically described, and illustrated in the accompanying drawings, wherein is shown an embodiment of the invention, but it is to be understood that changes, variations and modifications can be resorted to which fall within the scope of the claims hereunto appended.

20 In the drawings wherein like reference characters denote corresponding parts throughout the several views:

Fig. 1 is a front elevational view of the girdle according to the present invention,

25 Fig. 2 is a rear elevational view,

Fig. 3 is a left side elevational view of the side of the girdle,

Fig. 4 is a right side elevational view of the side of the girdle,

30 Fig. 5 is a plan view illustrating the cutting of the pattern for the front,

Fig. 6 is a plan view illustrating cutting of the pattern for the rear.

Referring to Figs. 5 and 6, there are two front 35 panels 10 and 11 for the cuff, each of two-way stretch material, and four lower panels 12, 13, 14 and 15. Panels 12 and 15 are of two-way stretch material, whereas panels 13 and 14 are of one-way vertical stretch material.

40 At the rear of the garment there are two cuff panels 16 and 17, forming the cuff, both of two-way stretch material, and three lower panels 18, 19 and 20 forming the lower part of the girdle. Panels 18 and 20 are of two-way stretch material and panel 19 is of one-way vertical stretch material.

An important feature of the cut of the present 45 garment is the fact that the front sections are separated at 21, 22, 23, 24, 25 and 26, causing controlled gathering at these points when the garment is sewn together. Moreover, it will be noted that the corners 27 and 28 extend beyond the corners 29 and 30 and that the corners 31 and 32 extend beyond the corners 33 and 34. In ad-

dition, the corners 35 and 36 extend beyond the corners 37 and 38.

The spacings 24 and 26 between the panels 12 and 13 and 14 and 15, respectively, are at a maximum adjacent the middle portions 39 and 40 and 41 and 42 of the panels 12 to 15, inclusive. They become minimum as indicated at 43, 44, 45 and 46 adjacent the lower parts of the panels 12, 13, 14 and 15. The spacing 25 also is at a maximum at the middle portions 40 and 41 of the panels 13 and 14, but the rate of decrease of the spacing to the narrower portions 47 and 48 is much less rapid than with the openings 24 and 26.

It will also be noted that whereas the edges 49 and 50 are single curves, scalloped toward each other and the edges 51 and 52 are single curves bowed outwardly, the edges 53 and 54 and 55 and 56 are double curves, the curvature of each being so designed as to substantially separate at 24 and 26 when the ends are together.

It will be also noted that at points 29 and 30 the sections 10 and 11 are at the waistline whereas at points 60 and 61 the points are substantially below the waistline. Positions 62 and 63 will be substantially above the waistline, which is indicated by the line 64. The double arrows 65, 66, 67 and 68 indicate two-way stretch, whereas the double-headed single arrows 69 and 70 indicate one-way stretch.

In Fig. 6 is shown the rear sections of the girdle. The upper two panels 16 and 17 forming the cuff are of two-way stretch material, as indicated at 75 and 76. The lower two side panels 18 and 20 are also of two-way stretch material, as indicated at 77 and 78. The rear panel 19 is of one-way stretch material as indicated at 79.

The upper two panels 16 and 17 meet at the points 79 and 80 and separate, as indicated at 81, adjacent the top corners 82 and 83. The edges 40 84 and 85 are curved inwardly.

The upper corners 86 and 87 are above the waistline while the lower corners 88 and 89 are at the waistline. The corners 79 and 80 are separated by the space 90 from the upper curve 91 of the panel 19 and when joined to the edge 91, will be substantially below the waistline. The space 90 narrows at 92 and 93 until it comes to the ends or corners 94 and 95 which joins the corners 88 and 89, respectively.

The middle panel 19 has the double curved side edges 96 and 97 which bulge at 98 and 99 and which are withdrawn at 100, 101, 102 and 103 to form the spaces 104, 105, 106 and 107 in respect to the correspondingly shaped edges 108 and 109 of the panels 18 and 20.

It will be noted that the corners 110 and 111 of the center panel extend above the corners 112 and 113 of the panels 18 and 20. The lower edges 114, 115 and 116 are all aligned as indicated.

In joining the sections 10 to 20 of Figs. 5 and 6 together, as indicated in Figs. 1 to 4, the fagoting or open stitching is utilized, as indicated at 125, 126, 127 and 128 on the front of the garment and at 129, 130 and 131 on the rear of the garment. Closed stitching is utilized at 130, 132, 133, 134 and 135 at the lower portions of the cuff and also at 136 on the left side and 137 on the right side.

A slide fastener 138 is utilized, extending from the middle 139 of the panels 15 and 20 up to

the top 140 of the cuff C. The opposite side is provided with a pocket 141 in which fits the coil or spiral bone member 142, which may be interiorly protected by a strip of plush.

5 The straight bones 143, 144, 145 and 146 are utilized in the cuff and they extend obliquely to points 147, 148, 149 and 150 at the lower edge of the cuff. The pockets for the bones 143, 144, 145 and 146 are interiorly lined with plush.

10 Two pads are desirably utilized at 151 and 152 at the back, as indicated in Fig. 2, for reinforcement purposes. The elements 10, 11, 12, 15, 16, 17, 18 and 20 are made of two-way stretch power net, or Leno, while the remaining sections are 15 desirably made of one-way stretch fabrics such as satin Lastex.

The embodiment of the invention shown and described herein is to be considered merely as illustrative, as the invention is susceptible to variation, modification and change within the spirit and scope of the appended claims.

Having now particularly described and ascertained the nature of the invention, and in what manner the same is to be performed, what is claimed is:

1. A woman's girdle having a lower thigh encircling portion extending from about the waistline downwardly to cover the thighs of the wearer and an upper diaphragm encircling cuff portion

30 encircling the diaphragm of the wearer and consisting of an inverted, conical funnel structure extending upwardly from the waistline to slightly above the diaphragm of the wearer, the upper and lower portions being connected by seaming around the waistline and the lower portion consisting of a plurality of vertically extending panels of one-way and two-way stretch elastic fabrics, the adjacent vertical side edges of which vertically extending panels are gathered together and seamed together by stitching along the front and sides of the garment.

35 2. The girdle of claim 1, in which the front and back of the upper portion are each provided with a plurality of spaced vertically extending stiffening bone members extending upwardly from the waistline to the top edge of the garment.

3. The girdle of claim 1, in which the side panels are formed of two-way stretch fabric and the front and back panels are formed of one-way stretch fabric.

40 4. The girdle of claim 1, in which the seaming along the waistline extends to somewhat below the waistline at the front and back of the garment and extends to the waistline at the sides of the garment.

45 5. The girdle of claim 1, the upper edges of the lower portion of the girdle being gathered by said stitching to the lower edges of the cuff portion.

ETHEL R. KAUPP.
